UNITED STATES PATENT OFFICE.

WILLIAM D. HARTMAN, OF FORT WORTH, TEXAS.

TAG FOR KEYS AND OTHER ARTICLES.

1,258,896.

Specification of Letters Patent. Patented Mar. 12, 1918.

Application filed March 28, 1914. Serial No. 827,939.

To all whom it may concern:

Be it known that I, WILLIAM D. HARTMAN, a citizen of the United States, residing at Fort Worth, in the county of Tarrant and 5 State of Texas, have invented certain new and useful Improvements in Tags for Keys and other Articles, of which the following is a specification.

My invention relates to tags and particularly tags for keys for hotels and other places, and the object is to provide tags to which keys may be attached and locked. A further object is to provide tags in which the numbers of rooms may be carried and 15 which will carry advertising cards. Another object is to provide tags by which keys may be sent by mail. It is well known that guests frequently carry away keys thoughtlessly. The object is to provide a tag by 20 which a key can be returned by mail. Another object is to provide a tag which can be used for a baggage check. Other objects and advantages will be fully explained in the following description and the invention 25 will be more particularly pointed out in the claims.

Reference is had to the accompanying drawings which form a part of this application.

30 Figure 1 is a front view of a tag and Fig. 2 is a rear view of the same. Fig. 3 is an edge view of the same. Fig. 4 is a longitudinal section of the locking devices on an enlarged scale. Fig. 5 is a plan view of the 35 key holder. Fig. 6 is a plan view of a releasing key. Fig. 7 is a plan view of the lock. Fig. 8 is a side elevation of the device adapted to be attached to the trousers. Fig. 9 is an edge view of the same.

40 Similar characters of reference are used to indicate the same parts throughout the several views.

The key tag may be made of a piece of leather or other suitable material bent to 45 fold together and having one part 1 and the part 2 folded together as shown in Figs. 1 to 3. A card 3 may be carried within the fold for the room number and rates for the hotel and a card 4 may be carried for advertising purposes. The cards 3 and 4 may be 50 protected by sheets of isinglass or other transparent sheets, isinglass being preferable because it is flexible. A lock 5 is permanently attached to one of the parts 1 or 2 by 55 means of the perforated arms 6. The lock has the edges 7 turned to form a keeper for

the key holder 8 which is adapted to slide down in the lock. The lock 5 has a tongue 9 struck therefrom which locks the key holder 8 within the tag. The tongue 9 is 60 sprung out of the plane of the body. The holder 8 has a tongue 10 sprung out of the plane thereof. The tongue 9 is adapted to pass through the slot which is made in the holder by cutting the tongue 10 therefrom. 65 The holder is formed by bending a reduced portion 11 to form a loop for the key. The inner end of part 11 serves to press the tongue 9 through the slot in the part 8 to unlock the holder from the lock 5. When 70 holder 8 is shoved down in the part 5, the tongue 9 will spring up through the slot in part 8 and when the holder is drawn back the tongue 9 will ride up on the part 8 and thus lock the holder in the lock. As a further 75 precaution against removal of the holder a notch 12 is formed in the bottom of the lock 5 and a tongue 13 is struck from the holder 8 and adapted to enter the notch 12. The holder 8 cannot be inserted in the 80 lock without a key because the tongue 13 will catch in the notch 12. By means of a key 15 which may be inserted between the holder 8 and the part 14 of the lock, the tongue 13 may be pressed out of the notch 85 12 so that the holder 8 may be inserted in the lock 5. The holder is then shoved down in the lock until the tongue 9 springs through the slot in the holder 8. The holder 90 is then drawn back toward entering point. 95 The tongue 13 will spring down in the notch 12 and thus lock the holder in the lock and the holder cannot be removed without the key 15. When the holder is to be removed for putting on a key or for other purpose, 100 the key 15 is inserted to press the tongue 13 out of notch 12. The holder is then shoved down in the lock until the tongue 9 will leave the part 8 and rest over the slot in part 8. Then pressure on the inner end of the part 11 above the tongue 10 will force the tongue 9 far enough down so that the part 8 can be withdrawn. Thus a key cannot be locked in the tag without a special tag key or release key 15.

105 The form of the device shown in Fig. 8 and Fig. 9 is provided with a clasp 16 which is adapted to hang on the trousers waistband. Tongues 17 may be struck from the hook 16 to prevent removal of the hook 110 from the trousers.

The advertising cards 4 may be carried

in the tags and the tag may be provided with a button 18 attached to one fold and a button hole 19 in the other fold so that the advertising cards may be inserted and removed. The key holder 8 may be long enough to catch the cards, as shown in Fig. 4. A hook 20 may be formed on the end of the holder 8 to catch the cards. The cards have slots 21 cut therein so that the hook 20 will engage the cards. The cards will be locked in place and cannot be removed without a key. The hook will engage the card when shoved down as previously described, and when the holder 8 is drawn back to locking position, it will draw the card up under the covers 1 and 2 so that a person cannot release the cards until the holder is unlocked and shoved down to be released as heretofore described.

20 What I claim, is,—

1. A key tag and means for locking a key thereto comprising a holder having a loop for engaging a key, said tag having a recess for receiving the holder, a lock embedded 25 in the tag and having a tongue struck therefrom and having a recess therein, and said holder having a lug engaging said recess and having a tongue struck therefrom to form an opening to receive the tongue formed on said lock, the tongue of said holder serving as a releasing means for removing the holder from the lock.

2. A key tag and advertising device comprising a body, cards inserted in said body, 35 said body having windows for exposing said cards, a lock embedded in said body, and a key holder consisting of a bent strip of metal with the ends thereof inserted in said lock, and said lock and said holder having interlocking 40 members by which the holder and

the lock are locked together and one member of said holder serving as a releasing means.

3. A key tag and advertising device comprising a body, cards inserted in said body, 45 a lock embedded in said body, a key holder consisting of a folded strip of metal and inserted in said lock and having a hook to engage said cards, and means for locking the holder and lock together and one member of 50 said holder serving as a releasing means.

4. A key tag and advertising device comprising a body, cards inserted in said body, a lock embedded in and attached to said body, a key holder consisting of a piece of 55 metal folded and forming an eye for a key and having the other end inserted in said lock and having one arm of the fold extended to form a hook to engage said cards, means for locking said holder and lock together, and a key for releasing the holder from the lock.

5. A key tag and advertising device comprising a body, cards inserted in said body, a lock inserted in and attached to said body, a 65 key holder having an eye at one end to receive a key and having the other end projected through said lock and having a hook formed thereon to engage said cards, said holder and said lock having interlocking 70 members whereby the holder and the lock are locked together and the key is locked in said eye and the cards are locked in said body.

In testimony whereof, I set my hand in the presence of two witnesses, this 16th day 75 of March, 1914.

WILLIAM D. HARTMAN.
